INVENTOR—
Thomas Lund

UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

STAMPING MACHINE.

1,421,511.

Specification of Letters Patent. Patented July 4, 1922.

Application filed May 1, 1918. Serial No. 231,842.

To all whom it may concern:

Be it known that I, THOMAS LUND, a citizen of the United States, residing at Beverly, in the county of Essex and State of Massachusetts, have invented certain Improvements in Stamping Machines, of which the following description, in connection with the accompanying drawings, is a specification, like reference characters on the drawings indicating like parts in the several figures.

This invention relates to stamping machines and especially to such machines in which the impression mechanism is controlled by key mechanism to determine the character of the symbol to be printed.

An object of the invention is to provide simple and effective controlling means for connecting a stamping member having a plurality of impression surfaces with a series of keys for controlling it. For the attainment of this object, I prefer to employ a curved lever connected with the stamping member, and with which the series of keys contact at different distances from its fulcrum. This causes the lever to swing through different angles, and, by suitable connections, as intermediate toothed members, to so move the stamping member that different impression surfaces are brought into action.

Another object of the invention is to furnish satisfactory means for maintaining the selected impression surface in its position for stamping. To this end, I associate with a series of keys a locking member common to all. Preferably, the parts are so organized that a depressed and locked key of the series is released by actuating another key of said series. There is also shown a special release key for use when it is desired that no impression shall be produced.

Other objects will be hereinafter developed, reference being had to the accompanying drawings, in which—

Fig. 1 is a front elevation of one embodiment of my improved stamping machine;

Fig. 2 is a side elevation looking from the right in Fig. 1;

Fig. 3 is a front elevation of the key mechanism, parts being broken away and in section;

Fig. 4 is a vertical section on the line 4—4 of Fig. 3; and

Fig. 5 is a transverse sectional detail on the line 5—5 of Fig. 3.

The operating elements of the machine are supported by a casing comprising a main lower portion 10 and an upper portion 12 extending in a generally vertical direction above the lower portion, and being shown of greater width laterally but of less depth from front to rear of the machine. The front of the base 10 of the casing is recessed between forwardly projecting portions, and through a lower horizontal surface 14 rises a work-supporting and pressure member 16 mounted to move in ways 18. Pivoted between depending arms 20 from the work-support 16 is the upper link of a toggle 22, the lower end of the companion link being articulated to a slide 24 mounted for movement through a lug 26 near the bottom of the casing. The upward travel of this slide is limited by a collar 28 threaded upon the bottom and contacting with the under side of the lug 26. Between the top of the lug and a collar 30 threaded on the upper portion of the slide is a helical spring 32, which holds the collar 28 normally in contact with the lug. By a change in the position of the collar 28, the height to which the work-support 16 is raised by the toggle may be varied, while an adjustment of the collar 30 changes the tension of the spring 32 and thus the resistance of the support to yielding when the impression is produced in the work.

Pivoted at the center of the toggle 22 is an eccentric rod 34 surrounding at its opposite extremity an eccentric 36 secured upon a shaft 38 journaled in the portion 10 of the casing. This shaft 38 is rotatable through spur gearing 40 from a shaft 42 carried in the casing parallel to the shaft 38, and being driven by power applied through a pulley 44. The gear upon the shaft 38 is normally loose thereon but may be connected to it to compel its rotation by a clutch indicated at 46, this being held out of engagement by a spring 48 and actuated to cause the rotation of the shaft through a rod 50 controlled by some such device as a treadle (not shown).

Above the recess in the portion 10 of the

frame is fixed a horizontal spindle 52, on which are mounted, side by side to turn between opposite cheeks of the frame, a series of stamping members furnished by disks 54. 5 These disks are shown as segmental, each bearing upon its periphery a series of impression surfaces 56 arranged to produce on the work the symbols to be stamped. The maximum number of impression surfaces 10 shown upon any one of the disks is ten, and the symbols may consist of the digits from zero to 9, or letters, or other characters, only such of the impression surfaces of each disk being utilized as are necessary to produce 15 the desired indications. The disks are preferably heated to increase the legibility of the impression upon the work by a device 58, here shown as in the form of an electric unit contained within the tubular spindle 52, current being delivered to the unit through leading-in conductors 60.

To set these stamping members so any of their impression surfaces may be caused to come into alinement and cooperation with 20 the work-support, a key mechanism is provided in the portion 12 of the frame. A front plate 62 has formed in it vertical series of openings through bosses 64, the series corresponding in number to the die-disks, and each series containing as many keys as there are impression surfaces upon the corresponding disk. Sliding within the openings in the front plate are the spindles 66 of keys, the heads or finger pieces 68 of 25 which are located outside the front plate. They are limited in their outward movement by members 70 pinned to the inner end of each spindle, each of these members being forced into contact with the inner extremity 30 of the corresponding boss by a helical spring 72 surrounding the spindle within the opening. The head or finger piece 68 of each key bears the symbol which is controlled by 35 this key on the respective disk. Fig. 1 of the drawings shows these for a machine arranged for stamping designations upon parts of shoes, two rows of keys at the right having size designations, followed by a row for the half size; then two rows of width symbols, two of match marks, and six of case 40 numbers. Fulerumed upon a rod 74 at the top of the portion 12 of the casing is a series of curved levers 76, the edges of which are alined with the vertical rows of key spindles. 45 The lower extremities of the levers, except that at the center, are offset laterally from the upper portions at 78 to bring them into substantial alinement with the respective die-disks, and are here each joined by a link 50 80 with a rocker arm or lever 82 pivoted upon a spindle 83 extending across the upper portion of the base 10 of the casing, each rocker arm having formed upon its lower end a segmental gear 84. The rocker arms 82, shown broken away in Fig. 3, may be off-

set, if necessary, at their lower ends to bring the segmental gears 84 into mesh with gear-segments 86, preferably formed on the rear of each die-disk. Springs 88, connecting the levers with the inner side of the front plate 62, draw the levers forwardly toward the rows of keys, and hold the die-disks in their inactive positions, in which none of the impression surfaces is opposite the work-support. This relation is as illustrated in Fig. 2 of the drawings. All the keys upon depression move through equal distances, or until their heads contact with the outer face of the plate 62. The end of each spindle, operating with the alined lever, swings it about its fulcrum through an angle determined by the distance which the particular key actuated is situated from the fulcrum and by the portion of its movement during which it is in contact with the lever. The second relation may be varied by locating the edge of the lever with which the key spindles contact at different normal distances therefrom, as by curving its edge. By properly proportioning the elements, the depression of any key is caused to rotate the disk to which this series of keys corresponds, through such an angle that the symbol upon the impression surface brought over the work-support will be the same as that borne by the key depressed.

Any key of a series is locked in its actuated position, thus holding its die-disk in the proper relation to stamp the desired symbol upon the work, by latching means, preferably common to the key series. This means consists of a bar 90 pivoted at its ends upon plates 92 secured to the upper and lower rows of bosses 64. Along the inner edge of each bar is a continuous latching projection 94, this projection having an inclined face, against which rests oppositely inclined faces upon the members 70 of this key series. Each bar is held in normal contact with the members 70 by a spring 96 having one arm secured to the bar and the opposite arm contacting with a pin 98 projecting from one of the plates 92. Between the latch bars, slots are formed in the plates to allow the movement of the levers 76.

When any one of the keys is depressed, the inclined surface of the member 70 rides over the incline upon the latch bar, and, when the top of the member 70 reaches the bottom of the latch bar projection, the latter is forced over it by the spring 96 to retain the key. At this time practically the full stroke has been made, so that the head of the key is in close proximity to the surface of the plate 62, as is illustrated in Fig. 4 of the drawings. The lever actuated by the key has turned the corresponding disk through such an angle that the symbol represented by the key is brought into alinement with the work-support 16 and is there 130

held ready to produce the impression by the latch bar. When another key in the same series is pressed down, the member 70 upon it forces aside the bar, and in so doing releases the key previously depressed before the projection 94 engages and locks the newly actuated key. It may be that it will not be desired to use any character in a particular row or rows, and to permit the restoration of the previously depressed keys and disks to their initial positions, a special release key 100 is provided in each series, these keys being, in the present instance, shown as arranged in a horizontal row at the bottom of the plate 62. The relation of the ends of the spindles of the release keys to their levers is such that their full travel does not move the levers from normal, but the member 70 upon any of the depressed release keys will force aside the latching bar and thus clear the series of disks in stamping position.

In using this apparatus, the operator presses the desired key in each series in which he wishes a symbol to be impressed upon the work. These are locked down as just described, with the impression surfaces of the die-disks alined with the work-support in the correct relation. The operator then places the work upon the support with its inner edge against a gage 102 and engages the clutch 46 by drawing down the rod 50. The rotation of the shaft 38 straightens the toggle and carries the work-support and work into co-operation with the impression surfaces of the dies, producing upon the work the inscription the symbols for which have been set up on the keyboard. As long as the same designations are to be printed, this operation is continued by successive introductions of work and depressions of the treadle. If the operator wishes to change any of the symbols, it is only necessary to depress the proper key or keys, releasing the previously adjusted keys and disks and bringing the new ones into position.

Having fully described my invention, what I claim as new and desire to secure by Letters Patent of the United States is:

1. In a stamping machine, a work support, a rotatable stamping member co-operating with the support and having a plurality of impression surfaces, a series of movable keys of equal length, corresponding to the impression surfaces, a lever with which the keys contact at different distances from its fulcrum, and connections between the lever and stamping member arranged to rotate said member positively to bring the proper impression surfaces into and out of their working positions.

2. In a stamping machine, a work-support, a movable stamping member co-operating with the support and having a plurality of impression surfaces, a series of movable keys of equal length corresponding to the

impression surfaces, a curved lever with which the keys contact at different distances from its fulcrum, connections constantly maintained between the lever and stamping member, and means for moving the work-support toward and from the stamping member to produce the impression. 70

3. In a stamping machine, a work-support, a rotatable stamping member having a plurality of impression surfaces, a lever, a series of keys of equal length and of equal stroke movable into contact with the lever to swing it through different angles, and connections between the lever and stamping member constructed and arranged to cause 75 such different angular movements to bring different impression surfaces into co-operation with the work-support and reverse movement of the lever to return the stamping member to normal. 80

4. In a stamping machine, a work-support, a rotatable stamping member mounted on a fixed axis and having a plurality of impression surfaces, a lever, a series of keys of equal length movable into contact with 90 said lever to swing it through different angles, means for restoring each key to normal, connections between the lever and stamping member constructed and arranged to cause such different angular movement to bring 95 different impression surfaces into co-operation with the work-support, and means acting upon the lever to return it and the stamping member to normal.

5. In a stamping machine, a work-support, a rotatable stamping member having a plurality of impression surfaces, a lever having a curved surface, a series of keys movable into contact with the curved surface of the lever to swing it through different angles, and connections between the lever and stamping member constructed and arranged to cause such different angular movements to bring different impression surfaces into co-operation with the work-support. 100

6. In a stamping machine, a frame, a work-support vertically movable therein, a rotatable stamping member journaled in the frame and having a plurality of impression surfaces any one of which may be turned 115 into alinement with the support, a lever, a series of keys movable into contact with the lever to swing it through different angles, and intermeshing toothed members connected to the stamping member and lever. 120

7. In a stamping machine, a work-support, a rotatable stamping member mounted on a fixed axis and co-operating with the support and having a plurality of impression surfaces, said member being 125 provided with a segmental gear, a lever, a series of keys for moving the lever, a lever having a gear segment meshing with the segment of the stamping member, and a link connecting the levers. 130

8. In a stamping machine, a work-support, a series of movable die-disks co-operating therewith and being provided with a toothed portion, a gear meshing with the teeth of each disk, a lever connected to each gear, and a series of keys spaced apart along the length of the lever for turning said lever upon its fulcrum, the throw of a key to the end of its stroke determining the extent of 10 rotation of its die-disk.

9. In a stamping machine, a work-support, a series of movable die-disks co-operating therewith and each being provided with a toothed portion, a gear meshing with the teeth of each disk, a lever connected to each gear, and a series of keys for turning said lever upon its fulcrum, the plural series of keys occupying a greater space laterally than the series of die-disks and their gearing, each of the levers having offset portions alined, respectively, with the die-disks and with the corresponding key series.

10. In a stamping machine, a work-support, a movable stamping member having a plurality of impression surfaces, a series of keys controlling the co-operation of particular impression surfaces with the work support, each key having a projection extending at one side of the series, and a continuous member mounted adjacent to the

series of keys and having a projection for engaging the projection of and locking any one of said keys in its controlling position.

11. In a stamping machine, a work-support, a movable stamping member having a plurality of impression surfaces, a series of setting keys controlling the co-operation of particular impression surfaces with the work-support, and a member common to the series of keys for locking any one of said keys in its controlling position, said locking member being arranged to release a locked key upon the actuation of another key of the series, there being included in the series of keys a release key acting independently of 45 setting effect upon the stamping member.

12. In a stamping machine, a work-support, a movable stamping member having a plurality of impression surfaces, a series of keys controlling the co-operation of particular impression surfaces with the work-support and each being provided with a projection, and a latch bar pivoted at one side of the series of keys and having a projection for engagement with those upon the 55 keys.

In testimony whereof I have signed my name to this specification.

THOMAS LUND.

Certificate of Correction.

It is hereby certified that in Letters Patent No. 1,421,511, granted July 4, 1922, upon the application of Thomas Lund, of Beverly, Massachusetts, for an improvement in "Stamping Machines," an error appears in the printed specification requiring correction as follows: Page 4, lines 29 and 30, claim 10, strike out the word "continuous" and insert the same before the word "projection" in line 31; and that the said Letters Patent should be read with this correction therein that the same may conform to the record of the case in the Patent Office.

Signed and sealed this 7th day of November, A. D., 1922.

[SEAL.]

KARL FENNING,

Acting Commissioner of Patents.
